UNITED STATES PATENT OFFICE.

DAVID B. KIMES, OF SPRING CITY, PENNSYLVANIA.

STITCH-CHANGING MECHANISM FOR KNITTING-MACHINES.

1,137,493.

Specification of Letters Patent. Patented Apr. 27, 1915.

Application filed October 26, 1912. Serial No. 727,902.

To all whom it may concern:

Be it known that I, DAVID B. KIMES, a citizen of the United States, residing in Spring City, Chester county, Pennsylvania, 5 have invented certain Improvements in Stitch-Changing Mechanism for Knitting-Machines, of which the following is a specification.

My invention relates to knitting and consists of improved mechanism for knitting machines.

My invention is particularly serviceable when used in connection with knitting machines such as are capable of producing different kinds of loops or stitches, as for example "regular" (including plain and rib knitting) or "tuck" knitting and which is used extensively in the production of tubular fabric for use in the manufacture of 15 undergarments where the bust and hip portions are made of "tuck" knitted fabric and the waist portion is made of "regular" 20 knitted fabric.

Heretofore, there have been various devices employed, on knitting machines of the above described type, for automatically effecting the changes in the character of the knitting, but as these devices were so complicated and unstable they often got out of 25 order or out of their proper combination for effecting a change without the operators noticing it and would often spoil fabrics by making the changes at improper places and lengths.

One of the chief objects of my invention is to equip a knitting machine with mechanism which will automatically actuate the machine to effect changes in the character of the fabric being produced and which will 30 be positive in its action and not get out of proper combination while running. Also, 35 that the construction will be such that if the mechanism be started in an improper position the same will right itself after a short 40 time and continue to make the desired combination of fabric structures.

Another object of my invention is that the same will be of simple construction, durable, and will require very little power to operate. 45 These objects and other advantages which will be described hereinafter, I attain in the following manner reference being had to the accompanying drawings in which:

Figure 1, is a side elevation of my inven-

tion shown attached to a circular knitting machine of a well known type; the outline of the knitting machine being shown in dot-and-dash lines; Fig. 2, is a side elevation, on a larger scale, than Fig. 1 of my invention, showing one position of the parts during the knitting operation; Fig. 3, is a view of similar nature to Fig. 2 and showing another position of the parts during the knitting of the fabric; Fig. 4, is a view similar to Figs. 2 and 3 and showing still another 65 position of the parts during the knitting of the fabrics; Fig. 5, is a plan view of Fig. 2; Fig. 6, is an end elevation of Fig. 2 looking in the direction of the arrow X at the right; Fig. 7, is a transverse sectional view taken 70 on the line a—a Fig. 6; Fig. 8, is a transverse sectional view taken on the line a—a Fig. 6 showing certain of the elements in different positions; Fig. 9, is a view similar to Fig. 8 and showing another arrangement 75 of the elements therein; Fig. 10, is a view similar to Fig. 9 showing certain of the elements in still another position; Fig. 11, is a fragmentary plan view showing certain of the elements in the position occupied in Fig. 80 7; Fig. 12, is a perspective view of a special form of chain link which I employ; Fig. 13, is a detached perspective view of a double or two-arm lever which forms a part of my invention; Fig. 14, is a detail perspective 85 view of a disk raising lever which I employ; Fig. 15, is a diagrammatic elevation indicative of a fabric which would be produced by the elements and the arrangement of a pattern chain as shown in Fig. 1; Fig. 16, is a 90 fragmentary side elevation showing a modified form of lever mechanism; and Fig. 17, is a fragmentary side elevation showing another modification of the elements of my invention.

Referring to the drawings, 1 is the main frame of a knitting machine having a stationary bed 2 secured thereon, said bed forming a support for a rotatable cam cylinder 3 having a cam 4 secured thereon. An 95 arm 5 is rigidly secured to the bed 2 and is provided with a bushing 6 for a vertical sliding rod 7 having a disk 8 secured to its upper end. Also, the arm 5 is provided with a shaft 9 which forms a pivotal bearing for a disk raising lever 10 and a chain actuated lever 11, the arm having in addition a fixed bearing for a lever extension 12; the 100 105

latter forming a pivotal support 13 for a pawl-controlling lever 14. The lever 14 is provided with a slot 15 into which extends a pin 11^b secured to the lever 11. The lever 10 is provided with an adjustable pin 10^a upon which the rod 7 rests.

The lower end 5^a of the arm 5 forms a journal for a rotatable shaft 16 which has secured to it a sprocket wheel 17, a ratchet wheel 18 and a bevel wheel 19. A pattern chain 20 is mounted on the sprocket wheel 17 and adapted to move thereby when the latter is rotated. The chain 20 is provided with links of variable heights and as shown in the present instance comprises the ordinary coupling links 21, medium height links 22 and 23, and high links 24 and 25.

A shaft hanger 26 is rigidly secured to the frame 1 and forms a support for a shaft 27 having secured thereon, adjacent one end a picker wheel 28 having pointed pins 29 projecting from its periphery and adapted to engage the knitted fabric as it passes downwardly from the machine. A bevel gear 30 is loosely mounted on the shaft 27 and is provided with a pin 31, and a sleeve 32 which is adjustably fixed to the shaft 27 by an adjustment screw 33 is provided with a projection 34 which extends for a portion of the circumference of the sleeve. The pin 31 on the gear wheel 30 is so placed that the latter may be rotated for a fractional part of one revolution without the pin 31 coming in contact with the projection 34, or vice versa, the sleeve 32 can be rotated for a fractional part of a revolution when the pin 31 and projection 34 are not in contact without the projection 34 moving the pin 31, as there is a movement in the present invention where the sleeve 32 forms the active member and tends to rotate the gear 30 through the medium of the pin 31, and there is also a movement when the gear 30 is moved independently of and at a greater speed in the same direction than the movement of the sleeve 32, and it will thus be seen that, as the movement of the said gear 30 moves faster than the movement of the collar or sleeve 32 during the previously mentioned independent movement of the said gear 30, there must be provision for the movement of the pin 31 without the latter effecting the movement of the sleeve 32 for the reason that the latter receives its movement through the medium of the wheel 28 from the fabric moving downwardly and that if the wheel 28 received a motion greater than the speed of the "take up" of the fabric being produced, the same would result in the fabric being torn, stretched or otherwise injured.

A bracket 35 having one end supported by the shaft 16 and the other end supported by the shaft 27 forms a journal for a shaft 36 having secured at one end a beveled gear 37 which meshes with the gear 19 on the

shaft 16, and has secured on the opposite end a beveled gear 38 which meshes with the gear 30.

A double ended lever 39 is pivoted at 40 to the frame 1 and has pivoted at one end an antifriction wheel 41, and, at the opposite end, a pivoted pawl 42 adapted under certain conditions to engage the teeth of the ratchet wheel 18. A tension spring 43 has one end secured to the lever 39 and the other end secured to the frame 1 and acts to keep the antifriction wheel in the path of and so as to be engaged by the cam 4 during each revolution of the cam cylinder 3. The lever 10 is provided with a forked projection 10^a; the depending prongs 10^b and 10^c forming a forked end. The high links 24 and 25 are cut-away at 24^a and 25^a respectively and the lever 11 is so arranged that its forward end 11^a rests on the chain links on the sprocket wheel 17. Also, the forked end 10^a on the lever 10 is of such a length that the prongs 10^b and 10^c straddle the said end 11^a of the lever 11. A stop 5^b on the arm 5 acts to limit the lower movement of the lever 10, such a position of the lever being shown in Figs. 1, 2 and 4, and showing the prongs 10^b and 10^c slightly clear of the links 21 on the chain. Also, in this position of the lever 10, the sliding rod 7, and disk 8 are in their lowest position, and the disk 8 is clear of the "regular" knitting switch 44 and the "tuck" switch 45; said latter switches being of any ordinary construction, and may be of the type shown in the accompanying drawings.

A pawl-disengaging lever 46 is pivotally mounted at 47 to the frame 1 and is provided with a plate extension 48 adjacent its upper end; said plate being of such a width as to extend between the ratchet wheel 18 and the sprocket 17 as clearly shown in Fig. 6. The lever 46 is provided at its opposite end with a heavy weight 49 which always tends to move the plate in the direction of the arrow shown in Fig. 1. While the pawl 42 is so placed as to engage the teeth of the ratchet wheel 18, it is of such a width that it extends beyond the ratchet wheel 18 and is therefore normally held out of engagement of the teeth of the ratchet due to the upward pressure of the plate 48 on the lever 46; such a position being clearly shown in Figs. 1 and 4. The free end 14^a of the lever 14 also normally rests on the top of the plate 48 and the free end 11^a of the lever 11 normally rests on the links 21 of the chain 20. A detent pawl 50 is pivoted at 51 to the arm 5 and acts to prevent back lash of the ratchet wheel when the latter is moved as will be more fully discussed hereinafter.

When a machine is equipped with my invention as shown in Fig. 1, the same will operate to knit a fabric of the nature shown in Fig. 15; the same being composed of a sec-

tion of "tuck" stitch knitted fabric as indicated from A to B; then a section of "regular" knitted fabric B to C; then another section of "tuck" stitch fabric from C to D; said latter "tuck" stitch fabric being greater in length than the "tuck" stitch fabric from A to B; then a comparatively few courses of "regular" fabric from D to A to the fabric starting at A again; and repeating this combination of fabrics throughout the entire knitting of the machine.

The elements of the machine in their position as shown in Fig. 1 are such that the disk 8 has previously been raised to a position in which the "tuck" switch 45, during the revolution of the head of the machine, has been shifted by coming in contact with the said disk 8 and thereby arranged the needle cams in a position to knit "tuck" stitch fabric; the disk 8 having dropped, in a manner hereinafter more fully described, to the position as shown in Fig. 1 and out of the path of the "tuck" switch. Therefore, in this position the machine is producing the "tuck" stitch portion of the fabric extending as shown in Fig. 15 from A to B; during the rotation of the head, including the cam cylinder 3, having the cam 4 secured thereto. The cam 4 for each revolution of the said head causes the antifriction wheel 41 to be depressed and thereby actuate the lever 39 having the pawl 42 thereon. However, as the pawl 42 is disengaged from the teeth of the ratchet wheel 18 at this stage of the operation, the pawl 42 will merely slide over the face of the plate 48 in the manner clearly shown in Fig. 1 and the ratchet wheel therefore will not receive any motion due to the action of the pawl 42. However, as the finished fabric moves downwardly from the machine it will contact with and thereby turn the picker wheel 28 and the shaft 27 secured thereto, and the projection 34 on the sleeve 32 will strike and move the pin 31 and thereby turn the wheel 30. This motion imparted to the wheel 30 is transmitted through the medium of the gears 38, 37 and 19 and the shafts 36 and 16, to the sprocket wheel 17, and the latter is thereby rotated in a direction indicated by the arrow in Fig. 1, and the chain 20 is moved thereover. This action of the machine continues until the high link 25 is moved into the position as shown in Fig. 2, the movement of the said link 25 into this position causing the top 25^b of the cut-away portion 25^a to strike and lift the free end 11^a of the lever 11 and through the medium of the pin 11^b in engagement with the slot 15 in the lever 14, causes the free end 14^a of the latter to move downwardly and thereby press against and move the plate 48 away from the pawl 42; allowing the latter to drop into mesh with the ratchet wheel as shown in Fig. 2. Then upon the next rotation of the head, the cam 4 will actuate the antifriction wheel on the lever 39 and cause the pawl 42 to move the ratchet wheel 18 to the extent of one tooth and thereby cause the highest portion of the link 25 to engage and raise the prongs 10^b and 10^c and thereby raise the lever 10 and the slide rod 7 and disk 8 into the position shown in Fig. 3 and with the disk 8 at a level to be engaged by and to shift the "regular" knitting switch 44 during the rotation of the head and thereby cause the machine to discontinue the knitting of "tuck" stitch fabric and to start knitting of the "regular" knitted fabric such as shown from B to C in Fig. 15.

While the lever 10 is raised in a position shown in Fig. 3 the end 11^b of the lever 11 is still held in a raised position due to the fact that it still rests on the portion 25^b of the link 25, and the end 14^a of the lever 14 consequently remains down and continues to hold the plate 48 out of engagement with the pawl 42. On the next rotation of the head the cam 4 will again strike the antifriction wheel 41 and actuate the lever 39; thereby causing the pawl 42 to again move the ratchet wheel 18 to the extent of one tooth. This latter movement of the ratchet wheel and the consequent movement of the sprocket 17, causes the high link 25 to be moved from under and away from the prongs 10^b and 10^c of the lever 10; thereby allowing the latter to drop in contact with the slot 15 and the disk 8 to drop clear of the switch lever; such a position being shown in Fig. 4. Also, as the link 25 is moved by the latter movement of the ratchet wheel it also moves from under the end 11^b of the lever 11; allowing the latter to drop. The weighted end 49 of the lever 46 then automatically acts to move the plate 48 to raise the end 14^a and move the pawl 42 out of engagement with the ratchet wheel 18. By moving the sprocket wheel 17 by a positive pawl and ratchet action direct from a working part of the machine each time a high link acts to lift the lever 10 as just stated, which action requires more power than when moving the ordinary low links 21 around the sprocket, I thus relieve the fabric of any undue strain and do not injure the same. However, at all other times but when either a link 22, 23, 24 or 25 is acting to raise the lever 10 the rotation of the sprocket wheel 17 is effected directly from the fabric contacting with the wheel 28. While the ratchet 18 is being moved due to the action of the pawl 42 the construction is such that the rotation of the shafts 16, 36 and gears 19, 37 and 38 are moved faster than when they are being rotated through the medium of the wheel 28, shaft 27 and sleeve 32. It will thus be seen that when the pawl 42 is actuated to move the sprocket 17, which movement necessarily is transmitted to the

- gear 30, that the pin 31, which was previously being moved by the projection 34 on the sleeve 32, will move away from the projection 34 at a greater speed than the continued movement of the projection 34 and thereby tend to increase its distance from the said projection 34. The distance between the pin 31 and the projection 34 will tend to increase during the said movement of the ratchet wheel by the pawl 42, which in the present instance is to the extent of two teeth, although, when the pawl 42 is disengaged as just mentioned in the operation of the machine, the ratchet wheel 18, sprocket wheel 17 and necessarily the gear 30 and pin 31 will stop until the projection 34 on the sleeve 32 catches up with the pin 31 and again moves the latter and thereby the sprocket 17 and the chain 20.
- 5 When the medium height link 22 reaches a position as that occupied by the link 25 shown in Fig. 2, the highest point of the link 22, which is substantially equal to the height of the portion 25^b of the link 25, will raise the lever end 11^a into the position occupied in Fig. 2 which will again cause the end 14^a of the lever 14 to depress the plate 48 and thereby allow the pawl 42 to engage with the wheel 18, then on the next rotation of the head the cam 4 will act through the medium of the antifriction wheel 41 and the lever 36 to operate the pawl 42 to move the ratchet wheel 18 to the extent of one tooth. This movement of the ratchet wheel, which is consequently imparted to the sprocket 17, tends to move the link 22 under and raise the prongs 10^b and 10^c and thereby cause the lever 10, sliding rod 7 and disk 8 to be raised into a position so that the latter will be struck by the "tuck" fabric switch 45 and thereby cause the machine to be changed so as to again knit "tuck" stitch fabric, such for example, as indicated from C to D in Fig. 15. Then upon the next rotation of the head the ratchet wheel 18 will again be moved by the pawl 42; this latter action causing the link 22 to be moved away from the prongs 10^b and 10^c of the lever 10 and also from the end 11^a of the lever 11 allowing the lever 10 to drop against its stop 5^b and thereby lowering the disk 8 out of the path of the switch levers and also allowing the pawl 42 to be disengaged from the ratchet wheel 18 in the manner heretofore described. Also, when the pawl 42 is disengaged as just stated the pin 31 has no motion until the projection 34 on the sleeve 32 again catches up therewith as previously described.
- 65 After the passing of the link 22 as just stated, the machine will continue to produce "tuck" fabric until the high link 24, which is similar to and acts the same as the link 25, again changes the machine so as to produce "regular" fabric. However, as shown in the drawing the distance between the high link 24 and the medium height link 23 is such that there will be a quick change, due to the medium height link 23, which is similar to the medium height link 22, to quickly change again after knitting a small portion of "regular" fabric from E to the next repeat of A, to knitting "tuck" fabric which it will continue to knit similar to the portion from A to B in Fig. 15; thus forming an automatic repeat of any combinations of fabric.
- The "regular" portions of fabric which are produced, due to the action of the high link 24 and until the link 23 changes the machine to "tuck" fabric again, is represented in Fig. 15 from D to the repeat of A and produces narrow portions of "regular" knitted fabric which may be used as gage lines for cutting the fabrics into garment lengths; the portion of each length from A to B serving to form the bust portion of the garment; that from B to C forming the waist portion of the garment, and that from C to D forming the hip and leg portions of the garment. While the machine, as shown in the drawing, will act to form four changes before a repeat a chain 20 having any combination of changes can be applied to the sprocket wheel 17.
- 100 Heretofore there have been machines manufactured for making changes in the character of fabric which has a plurality of chains and sprockets; one chain acting as a key chain to determine the movement of another chain for effecting the changes. However, as these chains had to operate in proper combination and required skill and much attention for their manipulation and changes in order to bring the proper combinations the same were not desirable and were often the cause of imperfect work which often caused great loss to the manufacturer. With my invention I use but one chain which is positive in its operation and will only tend to actuate the machine as predetermined by the links therein.
- 105 With my invention if a machine is started before or after the proper link has acted upon the levers 10 and 11 as determined by the character of fabric desired, the mechanism will right itself after a fractional part of a garment length has been produced. For example, suppose the operator desired to produce garment lengths of the particular combination as shown in Fig. 15, and instead of starting the machine when the link 25 is just ready to act, would have the portion of the chain which is between the links 25 and 22 directly beneath the prong
- 110 115 120 125 130

portion 10^b and 10^c of the lever 10. The machine thus improperly started will knit the fabric as prescribed by the arrangement of the links 34 until the high link 25 comes in contact with and raises the lever 10, after which the machine will continue to knit the proper combination of fabrics. Thus a machine constructed in accordance with my invention will not continue to make improper lengths of goods as heretofore was true in machines of this type on the market.

In Figs. 7, 8, 9 and 10 I have endeavored to clearly show the relative movements between the pin 31, secured to the gear 30 (the latter being loosely mounted on the shaft 27), and the projection 34 on the sleeve 32 (the latter being keyed to the shaft 27). In Fig. 7 the projection 34 and the pin 31 are shown in a position when the pawl 42 is held out of engagement with the ratchet 18, and the projection 34 is driving the gear 30 through the medium of the pin 31. Fig. 8 shows the arrangement of the pin 31 and the projection 34 while the pawl 42 is moving the ratchet 18 and the pin 31 is, due to the construction of the several parts of the machine, moving at a greater speed and away from the projection 34; the latter moving in the same direction but at a slower speed. Fig. 9 shows the pin 31 having moved its greatest distance away from the projection 34 due to the movement of the ratchet wheel for two teeth; this figure also shows the position of the said pin 31 when the latter is stopped, due to the disengagement of the pawl 42 from the ratchet wheel. Fig. 10 shows the projection 34 again caught up with the pin 31 from which time it will tend to again move the gear 30, through the medium of the pin 31 until the pawl 42 is again allowed to engage and move the ratchet 18.

While I have illustrated my invention as controlled in a specific manner both from the movement of the finished fabric and from a positive and movable part of the machine proper—it will be understood that the same may be actuated from any parts having the same relative movements.

Another particular advantage of my invention is that the movement of the chain 20 is controlled directly, excepting at the times when the machine is changing from one type of fabric to another, from the length of the finished fabric. Thus my invention causes a uniformity in the repeats of the fabric as it is more positive than operating the chain entirely from a working part of the machine proper, for the reason that while the rotations and movements of the machine may be constant, variations in the character of the yarn and of the tension thereon often cause variation in the length of the fabric at different times in the operation of the machine. With my invention, even though

there may be a variation in the length of the fabric in proportion to the rotation of the head, the lengths of repeats of the fabric will be uniform for the reason that the chain 20 or its co-acting elements will not move any faster than the speed of the fabric being finished, as it is obvious that even at the change points after the pawl 42 has racked the ratchet 18 at a greater speed than the production of the fabrics, there is a dwell of the ratchet 18 until such time as the projection 34 catches up to the pin 31. So that it will be seen that even though auxiliary pawl and ratchet mechanism is provided doing the "harder work" of actuating the machine to form the changes, the same is done in such a manner as not to interfere with the measuring of the proper fabric lengths directly from the fabric itself.

The stitch changing switches 44 and 45 as shown in dot-and-dash lines in the several figures of drawing are of any well known type and are carried by the rotatable head of the machine. These switches are so coupled together that when either one of them strikes the disk 8 and is deflected thereby it will simultaneously throw the other of the switches out of operation.

While I have described certain portions of the fabric as being "regular" knitted in contrast with "tuck" knitted portions of the fabric, it will be understood that my invention can be used in a machine for making any changes in the characters of the stitch being produced, for example, if the machine head is rigged to produce "ribbed" fabric and "tuck" fabric the same could be made to change from "rib" to "tuck," or if the machine is rigged to knit "plain" fabric and "drop" stitch fabric the same would be made to change from the "plain" fabric to the "drop" stitch fabric and vice versa. In other words, any change that the machine proper would be capable of producing can be effected by my invention.

While I have described the elements 11 and 14 as separate levers it will be understood that they act together and are really a double or two-arm lever. Also, the machine as illustrated is of the type known as a multiple feed underwear machine and well known on the market but it will be understood that my invention can be added to other types of machines if desired.

In the modification shown in Fig. 16 instead of having the double levers 11 and 14 as shown in the main views of drawing I provide a two-arm lever 52 made in one piece. In this case the end 53 is positioned to be engaged by the high links on the chain 20 to lower the end 54 and thereby press against and move the lever 46 and plate 48 away from the pawl 42 and thereby allow the latter to engage the ratchet 18 in a manner heretofore described.

In Fig. 17 I have shown the end 11^a of the lever 11, in the main views of drawing provided with a pendant weight 55; thus doing away with the lever 46 and counter balance weight 49. When the weight 55 is used, the pawl 42 will be moved directly by the end 14^a of the lever 14 and will tend to slide on the latter while disengaged from the ratchet 18. However, either the lever 46 or the weight 55 can be used to give the desired result. Also, in Fig. 17 I have shown the end 14^a of the lever 14 curved so as to prevent the pawl 42 from being moved too far from the ratchet 18 when being disengaged therefrom.

15 I claim:

1. The combination in a knitting machine of stitch changing mechanism; pattern mechanism; two devices, of which one is normally active, for actuating the pattern mechanism; and means for holding the other of said devices out of operative position, said pattern mechanism including a single member movable to release said holding means and operative to actuate the stitch changing mechanism.

2. The combination in a knitting machine of stitch changing mechanism; pattern mechanism; and two devices, of which one is normally active, for actuating the pattern mechanism, the latter including members successively operative to move the stitch changing mechanism into different active positions, said members also being movable to periodically effect the operation of the other of said devices.

3. The combination in a knitting machine of a supporting structure; stitch changing mechanism; pattern mechanism; two operatively connected levers pivotally mounted on the supporting structure; two devices for actuating the pattern mechanism; and means for normally holding one of said devices inoperative, said pattern mechanism being operative to move one of said levers to actuate the other lever to throw said latter device into operation, and being also operative to actuate said stitch changing mechanism during the operation of said latter device.

4. The combination in a knitting machine of a supporting structure; stitch changing mechanism; pattern mechanism; two operatively connected levers pivotally mounted on the supporting structure; two devices for actuating the pattern mechanism; and means for normally holding one of said devices out of action, said pattern mechanism including a member operative to move one of said levers and thereby actuate the other lever to cause said latter device to operate, said member also being operative to actuate said stitch changing mechanism.

5. The combination in a knitting machine 65 of a supporting structure; stitch changing

mechanism; a ratchet; pattern mechanism movable with the ratchet; means operated by the fabric produced for moving said pattern mechanism; a pawl for said ratchet; means actuated from a movable part of the machine for operating said pawl; two operatively connected levers pivotally mounted on the supporting structure; and means for normally holding said pawl out of action, said pattern mechanism being operative to actuate said levers to permit engagement of the pawl with the ratchet, and to actuate said stitch changing means during the operation of said pawl.

6. The combination in a knitting machine 80 of stitch changing mechanism; pattern mechanism; a device actuated by a movable part of the machine to operate said mechanism; means for normally holding said device out of action; and mechanism operated 85 by the movement of the fabric produced for actuating said pattern mechanism when said device is out of operation, said pattern mechanism including a single member operative both to release said holding means to effect 90 the operation of said device, and also to actuate the stitch changing mechanism.

7. The combination in a knitting machine of stitch changing means; a pattern chain having actuating links of different heights 95 and operative to move said stitch changing means into a plurality of different active positions; two devices for moving the pattern chain; and means for rendering inactive one of said devices, each of said links 100 being operative to actuate said latter means to permit the latter device to operate.

8. The combination in a knitting machine of stitch changing mechanism; pattern mechanism; two devices of which one is normally active, for actuating the pattern mechanism; and means for holding the other of said devices in an inactive position, said pattern mechanism including a single member operative to move said latter means to effect 110 the operation of said latter device and to actuate the stitch changing mechanism.

9. The combination in a knitting machine of stitch changing mechanism; a sprocket; a single pattern chain carried by the sprocket 115 and having actuating links of different heights operative to successively move the stitch changing mechanism into different active positions; a ratchet movable with the sprocket; a pawl for moving the ratchet 120 actuated by a movable part of the machine; mechanism periodically moved by said links to permit the pawl to engage the ratchet; and means actuated by the fabric produced for actuating said chain.

10. The combination, in a knitting machine having stitch changing mechanism, of a rotatable shaft; a sprocket keyed to the shaft; a pattern chain on said sprocket and having links of different heights,

ratchet movable with the shaft; a pawl for engagement with the ratchet; a movable cam on the machine for operating the pawl to move the ratchet and consequently the chain; means for actuating the stitch changing means and moved by the high links of the chain; a counter-balance lever for automatically disengaging the pawl from the ratchet; a two-arm lever, one of said arms of the latter being adapted to be engaged by the high links on the chain to move the other arm so as to free the pawl from the counter-balance lever and thereby allow the pawl to again engage the said ratchet; and means in engagement with and actuated by the movement of the fabric to move the said chain.

11. The combination, in a knitting machine having stitch changing mechanism, of a rotatable shaft; a sprocket keyed to the shaft; a pattern chain on said sprocket and having links of different heights; a ratchet movable with the shaft; a pawl for engagement with the ratchet; a movable cam on the machine for operating the pawl to move the ratchet and consequently the chain; means for actuating the stitch changing means and moved by the high links of the chain; a counter-balance lever for automatically disengaging the pawl from the ratchet; a two-arm lever, one of said arms of the latter being adapted to be engaged by the high links of the chain to move the other arm so as to free the pawl from the counter-balance lever and thereby allow the pawl to again engage the said ratchet; a second shaft; a wheel keyed to said latter shaft and having pins arranged to be engaged by the fabric during its movement from the machine; a member adjustably fixed to the latter shaft and having a projection; a gear loosely mounted on the shaft and having a pin extending into the path of the said projection; and means operatively connecting the said gear wheel to the first shaft to move the said chain.

12. The combination in a knitting machine having a rotatable head and stitch changing switches mounted thereon, of a shaft; a sprocket keyed to the shaft; a pattern chain mounted on said sprocket and having links of different heights; a ratchet movable in conjunction with the said shaft; a slideable rod having a disk thereon; a pivotally mounted lever positioned to be engaged and moved by the high links on the chain to move the said disk into a path to be engaged by any of the said switches; a pawl for engagement with the ratchet; a cam secured to a movable part of the machine for actuating the pawl to move the ratchet and consequently the pawl from the ratchet; a two-arm lever, one of said arms being positioned to be actuated by the high links on the chain to move the other arm into contact with the counter balanced lever to free the pawl from the latter and allow it to re-engage the ratchet; a second shaft; a wheel fixed to the shaft and having pins arranged to be engaged by the fabric during its movement from the machine; a member adjustably fixed to the latter shaft and having a projection; a gear loosely mounted on the shaft and having a pin extending into the path of the said projection; and means operatively connecting the said gear wheel to the first shaft to move the said chain.

13. The combination in a knitting machine having stitch changing means; a shaft; a sprocket keyed to the shaft; a pattern chain on said sprocket and having links of different heights; means for actuating the stitch changing means and operated by the high links of the said chain; a ratchet movable in conjunction with the said shaft; a pawl for engagement with the ratchet wheel; means for moving the pawl; a counterbalance lever for automatically disengaging the pawl from the ratchet; a two-arm lever, each of said arms being pivotally mounted to a fixed portion of the machine, one of said arms having a projection extending into a slot in the other of said arms so that when one arm is moved in one direction the other arm will move in the opposite direction, one of said arms being so arranged as to be engaged and moved by the high links on the chain and thereby move the other of said arms against the said counter-balance lever to free the pawl from the latter and allow it to re-engage the ratchet.

14. The combination in a knitting machine of stitch changing mechanism; a rotatable shaft; a sprocket keyed thereon; a pattern chain on said sprocket having actuating links of different heights; a ratchet movable with the shaft; a pawl for engagement with the ratchet and actuated by a movable part of the machine; means for disengaging the pawl from the ratchet; a lever having an arm positioned to be actuated by said links to move the other arm into engagement with said disengaging means to cause the latter to permit the pawl to engage the ratchet; and means operated by the fabric produced for operating said shaft.

In testimony whereof, I have signed my name to this specification, in the presence of two subscribing witnesses.

DAVID B. KIMES.
